UNITED STATES PATENT OFFICE.

JOHN G. JOHNSON, OF TACOMA, WASHINGTON, ASSIGNOR OF ONE-HALF TO JOHN R. KIELY, OF TACOMA, WASHINGTON.

FAN BELT.

Application filed May 18, 1920. Serial No. 382,201.

To all whom it may concern:

Be it known that I, JOHN G. JOHNSON, a citizen of the United States, and resident of the city of Tacoma, county of Pierce and 5 State of Washington, have invented certain new and useful Improvements in Fan Belts, of which the following is a specification.

My invention relates to improvements in belts, and more particularly to belts of that 10 character designated as automobile fan belts; the principal object of the invention being to provide a belt of novel construction, which possesses maximum wearing qualities, is strong and durable in use, wherein cracking 15 is eliminated and stretching is reduced to a minimum.

In accomplishing the objects of the invention, I have provided the improved details of construction, the preferred form of which 20 is illustrated in the accompanying drawings, wherein—

Fig. 1 is a side view of a fan belt constructed according to the present invention; a part of the binding strip being removed 25 for better illustration.

Fig. 2 is an enlarged view of a part of the belt.

Fig. 3 is a transverse sectional view of the same.

Fig. 4 is a transverse sectional view of a 30 belt of a different shape.

Referring more in detail to the drawings—

1 designates a fan belt constructed according to the present invention, which in its 35 preferred form consists of an endless core or belt body, formed of a plurality of strands 2 of rope, or the like, which are interwoven, twisted together or arranged parallel to each other in an endless core of any desired length

and bound together within a casing formed 40 of an endless strip 3 of pliable material such as leather or fabric which is wound spirally thereabout.

In order to prevent slipping of this binding on the core or body of the belt, the strip 45 is extended between strands of the body at spaced intervals, as is shown particularly at 4 in Fig. 1.

While I have illustrated the belt as being round in cross section, it is not desired that 50 the belt be made only in this form, as it is apparent that, as shown in Fig. 4, by the proper placing and varying the number of strands used to make up the core, it may be made flat, V-shaped or in other shapes. 55

It is apparent that a belt of this character would be strong, pliable and lasting and that cracking would be eliminated due to the flexibility of the core strands and their casing or binding. 60

Having thus described my invention, what I claim as new therein and desire to secure by Letters Patent is:

An endless belt of the class described comprising a core formed of a plurality of 65 twisted or interwoven strands of cording and a casing applied to said core comprising an endless, flat strip of flexible material wound spirally on the core with the convolutions thereof close together to entirely cover the 70 core and forming a smooth exterior surface, and said strip being extended at intervals beneath strands of the core for the purpose set forth.

Signed at Tacoma, Washington, this 11th day of May, 1920.

JOHN G. JOHNSON.
